CLAIM

Applicant claims the ornamental design for an interchangeable scrub brush or scrub pad for a floor maintenance vehicle, as shown and described.

DESCRIPTION

FIG. 1 is an upper perspective view of an interchangeable scrub brush or scrub pad for a floor maintenance vehicle of Applicant's design;

FIG. 2 is a front elevational view thereof;

FIG. 3 is a rear elevational view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a sectional view thereof taken along line 8-8 in FIG. 6;

FIG. 9 is a sectional view thereof taken along line 9-9 in FIG. 6;

FIG. 10 is an enlarged top plan view thereof illustrating the portion within circle 10 in FIG. 6; and,

(Continued)

See application file for complete search history.

FIG. 11 is a sectional view thereof taken along line 11-11 in FIG. 10.
The broken lines shown represent unclaimed subject matter and form no part of the claimed design.

1 Claim, 8 Drawing Sheets
